[57] CLAIM

The ornamental design for an overhead projector, as
shown and described.

DESCRIPTION

FIG. 1 is a top and left front perspective view of an
overhead projector showing our new design;

FIG. 2 is a top plan view thereof;

FIG. 3 is a rear elevational view thereof;

FIG. 4 is a right side elevational view thereof;

The broken-line showings of a projector head in FIGS.
1-4 are environmental only and form no part of the
claimed design.

FIG.1

FIG.2

FIG. 4

FIG. 3
